UNITED STATES PATENT OFFICE.

DAVID P. CLARK, OF DAYTON, OHIO.

TOY.

1,111,056.

Specification of Letters Patent. Patented Sept. 22, 1914.

Application filed July 9, 1913. Serial No. 778,170.

To all whom it may concern:

Be it known that I, DAVID P. CLARK, a citizen of the United States, residing at Dayton, in the county of Montgomery and 5 State of Ohio, have invented certain new and useful Improvements in Toys, of which the following is a specification, reference being had therein to the accompanying drawing.

10 This invention relates to toys and more particularly to wheeled toys of the self propelled type.

The object of the invention is to provide 15 a spring-propelled toy capable of traveling a long distance without the use of an excessively large spring; and further, to construct the toy after the design of an automobile with the winding crank at the front.

To these ends it is a further object of 20 the invention to provide the toy with a spring extending longitudinally thereof and so mounted and arranged as to develop a minimum amount of friction and to exert a large amount of power upon the driving 25 axle; and which is adapted to be wound or compressed by means of a crank at the front end of the toy.

In the accompanying drawings, Figure 1 30 is a bottom, plan view of a toy embodying my invention; Fig. 2 is a longitudinal, sectional view of a slightly modified form of the invention; Fig. 3 is a horizontal sectional view taken longitudinally of a toy embodying the invention, showing the 35 mechanism partly in elevation and partly in section, and Fig. 4 is a vertical longitudinal section showing the driving mechanism partly in section and partly in elevation.

In Fig. 1 of the accompanying drawings 40 I have illustrated one form of the invention, while in Fig. 2 I have shown a second form of the invention. In both forms it will be understood that the toy may be of any suitable character and may represent 45 any type of wheeled vehicle. In both of the forms here shown, however, I have chosen to make the toy in the form of an automobile.

Referring first to Fig. 1 the toy comprises a frame 1 mounted upon four ground 50 wheels, the front wheels, 2, being steering wheels, while the rear wheels, 3, are driving wheels and are rigidly secured to an axle 4. This axle is journaled in the side 55 members of the frame 1 and may be driven

in any suitable manner, preferably by securing thereto a pinion 5 coöperating with a driving member or gear 6 having a hollow hub 7 journaled in the transverse frame member 8. Extending longitudinally to the 60 frame is a shaft or guide rod 9. At its rear end this shaft is loosely mounted in the hollow hub 7 of the driving gear 6 and at its forward end is rotatably mounted in the transverse member 10 of the frame 1 and 65 projects beyond the said frame member, the forwardly projecting portion being adapted to receive a rotating device, such as a crank 11. Means are also provided for holding the shaft against rotation in one direction. 70 Preferably, this means comprises a ratchet wheel 12 rigidly secured to the shaft near its forward end and coöperating with a pawl 13 mounted on the frame. Coiled about the shaft 9 is a spring 14 which is connected at 75 one end to the shaft, preferably by securing it to the ratchet wheel 12 and is connected at its other end to the hub of the gear 6. In this form of toy I have also provided the rear axle with a detent to prevent its rotation in one direction, such as a ratchet wheel 15 coöperating with a pawl 16, the pawl having a projecting portion or handle 17 extending beyond the frame of the toy where it can be manually actuated to release 80 the axle. From the description it will be apparent that by actuating the crank 11 the spring 14 can be wound about the shaft 9 and the pawl and ratchet 16, and 15, will hold the axle against rotation during the 85 winding action and when the winding is completed the spring will be held against unwinding at its forward end by the pawl and ratchet 13 and 12. When it is desired to operate the toy the spring is released by 90 actuating the handle 17 to release the axle from the detent, thus permitting the driving member or gear 6 to rotate independently of the shaft 9 and transmit the power of the spring to the driving axle. By 95 means of this construction a very powerful spring may be mounted within the toy without consuming any considerable amount of space and by allowing the driving member to rotate independently of the support for 100 the spring and of all other parts connected with the spring, the friction is reduced to a minimum and the power is applied directly to the driving member so that a high degree of efficiency is obtained in the toy. In 110

actual practice it develops a power greatly in excess of the power developed by other spring toys of the same size.

In the form of the toy shown in Fig. 2 I have shown a different arrangement of the parts without departing from the principle involved. The frame of the toy is shown at 18 and it is provided with steering wheels 19 and drive wheels 20. The drive wheels 10 are mounted on an axle 21 having a driving pinion 22 rigidly secured thereto and meshing with a driving gear 23. Preferably, the driving gear 23 receives its motion through reducing gearing and to this end the gear 15 23 has rigidly secured thereto a pinion 24 meshing with a gear 25 which is rigidly secured to one end of a rod or shaft 26 which is journaled at its rear end in a supplemental frame member 27, which frame member 20 also supports one end of the pinion 24. The opposite end portion of the rod 26 has secured thereto a disk 28 and the end extends into the hollow end of a spring-supporting shaft or rod 29, the forward 25 end of which is journaled in a frame member 30 and extends beyond the end of the body of the toy where it is provided with a clutch member or other device 31 to connect it with a rotating device or crank. The shaft 29 also has secured thereto a detent, such as a ratchet wheel 32, which operates with a pawl 33. A spring 34 is coiled about the shaft 29, connected at one 30 end with the ratchet 32 and at the other 35 end with the shaft 26, preferably by securing the end of the spring to the disk 28. In this manner substantially the same effects are secured as are secured by the form shown in Fig. 1. The shaft 26 is loosely 40 journaled and offers very little resistance to the expansion of the spring and inasmuch as the rod on which the spring is mounted is not connected with the driving member the frictional resistance between the 45 spring and the shaft is reduced to a minimum and this small resistance does not interfere with the rotation of the driving shaft. In this form of the toy I have not shown any detent in the rear axle, it being 50 designed to prevent the rotation of the driving wheel by means of the hand that holds the toy while it is being wound. Obviously, however, the detent could be applied to this 55 form as well as the form shown in Fig. 1. While I have shown and described two 60 embodiments of my invention it will be understood that these have been chosen for the purposes of illustration and that I do not desire to be limited to the details of construction shown and described, for obvious 65 modifications will occur to a person skilled in the art.

Having thus fully described my invention, what I claim as new and desire to secure by Letters Patent, is:—

1. In a toy, the combination, with an axle, and wheels secured thereto, of a shaft extending longitudinally of said toy, a driving member mounted at the end of said shaft, rotatable relatively thereto and operatively connected with said axle, a detent mounted at the other end of said shaft to hold it against rotation in one direction, a spring coiled about said shaft and connected at its opposite ends with said driving member and said shaft, respectively, and means to rotate said shaft. 70

2. In a toy, the combination with an axle and wheels therefor, of a rotatable shaft extending longitudinally of said toy, a spring 80 coiled about said shaft, means for winding said spring, a detent to hold one end of said spring against unwinding movement and a driving connection between the other end of said spring and said axle, said connection comprising a shaft extending longitudinally of said spring and disconnected from the first-mentioned shaft. 85

3. In a toy, the combination, with an axle and wheels secured thereto, of driving 90 gearing connected with said wheels, a shaft connected with said driving gearing and extending longitudinally of said toy, a coiled spring extending longitudinally of said toy and connected at one end to said shaft and 95 having means at the other end thereof for winding the same and for holding the same against unwinding movement, and a support for said spring extending longitudinally thereof. 100

4. In a toy, the combination, with an axle, and wheels secured thereto, of driving gearing connected with said wheels, a shaft connected with said driving gearing and extending longitudinally of said 105 toy, a second shaft having one end hollow to receive the end of the first-mentioned shaft and having its other end rotatably supported, a spring coiled about said second shaft and having one end secured to the 110 first-mentioned shaft and having a winding device connected with the other end thereof, and means to hold said last-mentioned end of said spring against unwinding movement. 115

In testimony whereof, I affix my signature in presence of two witnesses.

DAVID P. CLARK.
